US0D1063062S

(12) **United States Design Patent** (10) Patent No.: **US D1,063,062 S**
(45) Date of Patent: ** Feb. 18, 2025

(54) **NASAL SPRAY DEVICE**

(71) Applicant: **Alkem Laboratories Limited**, Mumbai (IN)

(72) Inventors: **Ulhas Dhuppad**, Nashik (IN); **Babasaheb Aware**, Beed (IN); **Jitendra J. Gangwal**, Navi Mumbai (IN); **Satish Pandey**, Navi Mumbai (IN); **Vinodkumar Chaubey**, Raigad (IN); **G. Dinakaran**, Bangalore (IN); **Santhoshkumar Raji**, Vellore (IN); **Harisha Rajakumar**, Mysore (IN)

(73) Assignee: **Alkem Laboratories Limited**, Mumbai (IN)

(**) Term: **15 Years**

(21) Appl. No.: **29/852,811**

(22) Filed: **Sep. 9, 2022**

(30) **Foreign Application Priority Data**

Mar. 10, 2022 (IN) 360264-001

(51) LOC (15) Cl. 29-02

(52) U.S. Cl.

(57) **CLAIM**

The ornamental design for a nasal spray device as shown and described.

DESCRIPTION

FIG. 1 is a perspective view of the present invention.

FIG. 2 is a perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.
